F. T. OAKLEY

ROCKING HORSE

Filed March 5, 1925

FIG. 1.

FIG. 2.

FIG. 5.

FIG. 6.

Inventor
Frederick Thomas Oakley.

By Adam E. Fisher.

Attorney

UNITED STATES PATENT OFFICE.

FREDERICK THOMAS OAKLEY, OF PAWLING, NEW YORK.

ROCKING-HORSE.

Application filed March 5, 1925. Serial No. 13,117.

To all whom it may concern:

Be it known that FREDERICK THOMAS OAKLEY, a citizen of the United States, residing at Pawling, in the county of Dutchess and State of New York, has invented certain new and useful Improvements in Rocking-Horses, of which the following is a specification.

This invention is a rocking horse for children, and the object is to provide a toy rocking horse having novel means embodied for imitating the hoof beats of a real horse.

In the drawing

Figure 1 is a side elevation of the horse;

Figure 2 is a plan view of the rocker element or base;

Figure 3 is a horizontal section through the body of the horse;

Figure 4 is a transverse, vertical section;

Figures 5 and 6 are details of the front and rear legs respectively, sections of the hoofs being broken away so as to show the mounting of the hammers therein.

The invention consists of a body portion 1 formed in simulation of a real horse, and having a saddle 2 and bridle 3. The body portion is recessed out or mortised transversely on the under side, at the front and rear ends as shown at 4 so as to afford bearings or boxings for leg axles 5 which are journaled therein and secured in place by latches 6. The mortises 4 are enlarged at their outer ends in parallel planes extended

parallel with a vertical, longitudinal plane passed medially through the body portion, so as to form suitable leg sockets 7. Front and rear legs 8 and 9 are provided, the shoulders 10 thereof being pierced with axle holes 11 through which the ends of the axles 5 are passed, and the legs are thus pivotally or swingingly mounted in place in the sockets 7 upon the axles 5, the latter being releasably held in the mortises 4 by means of the said latches 6. The longitudinal play

45 of the shoulders 10 within their sockets is so regulated, that on the back and forth rocking motion of the horse as completed, the legs will be stopped abruptly short of a full or absolutely free swing, by the shoulders 50 impinging against the forward and rear sides of the said leg sockets 7, in imitation of the movements of the legs of a real horse in galloping.

The hoofs 12 of the four legs are hollowed out, as shown at 13, and apertures 14 are also cut through the walls of the hoofs.

Hammers or weights 15 are then suspended, pendulum-like, within these hollow hoofs by means of chains or cords 16. Rockers 17 are provided and supported in working relation by braces 18. A flat, arched body truss 19, is secured by its ends to the front and rear braces 18 and supported at its center by an upright 20. The body of the horse is rigidly secured to the upcurved, central portion of this truss 19 by screws 21 passed up through the truss into the under side or belly of the horse. The legs and mounting are so proportioned and adjusted that the hoofs 12 will not strike or impinge upon the rockers 17, but will swing back and forth clear of any interference as the horse is rocked upon the rockers 17.

In use, as the horse is rocked, the legs will imitate the motion and movements of the legs of a real horse, and at the same time the weights or hammers 15 will strike and beat against the sides of the hoofs, thereby causing sounds to issue through the apertures 14, in imitation of the hoof beats of a real horse.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. In a device of the kind described, the combination of a rocking horse having a body portion, rockers and legs, the legs being pivoted to the body portion and swinging independent of the rockers, the hoofs of the legs being hollow; and weights pendulously suspended within the hollow hoofs.

2. A rocking horse, comprising rockers braced together; an arched truss mounted on the rockers; a toy horse supported by its body portion resting upon and rigidly secured to the truss; legs with hoofs, the legs being pivotally attached to the body portion, the hoofs of the said legs being hollow; and weights pendulously suspended within the said hollow hoofs.

3. A rocking horse, comprising rockers; an arched truss on the rockers; a toy horse mounted by its body portion upon the arch of the truss, the said body portion having leg sockets formed therein; legs pivotally mounted within the said leg sockets and adapted to oscillate with a limited move-

ment in a longitudinal direction and free of the said rockers, the said legs including hollow hoofs having apertures through the walls thereof; weights pendulously suspended within the said hollow hoofs.

4. In a rocking horse having a body portion, rockers and legs, the legs being unattached to and swinging independent of the rockers; hollow hoofs for the legs; and weights pendulously mounted within the hollow hoofs.

5. In a rocking horse having a body portion and rockers, and legs moving independently of the rockers; hollow hoofs for

the legs, the said hoofs having apertures pierced through its walls; and weights pendulously mounted within the said hollow hoofs.

6. A rocking horse, comprising rockers; a body portion mounted above the rockers and moving therewith; legs pivotally mounted to the body portion and oscillating free of the rockers; hollow hoofs at the ends of the legs, the walls of the hoofs being apertured; and weights pendulously suspended within the hollow hoofs.

In testimony whereof I affix my signature.
FREDERICK THOMAS OAKLEY.
